DESIGN FOR A SET OF GAME PIECES

Edward J. Baker, Stockton, Calif.

Application February 19, 1940, Serial No. 90,355

Term of patent 3½ years

To all whom it may concern:

Be it known that I, Edward J. Baker, a citizen of the United States, residing at Stockton, in the county of San Joaquin and State of California, have invented a new, original, and ornamental Design for a Set of Game Pieces, of which the following is a specification, reference being had to the accompanying drawing, forming a part thereof.

pieces comprising the set of game pieces, embodying my new design, the remaining pieces being duplicates of those shown.

Figure 2 is a side elevation of any one of the game pieces shown in Fig. 1.

I claim:

The ornamental design for a set of game pieces, as shown and described.

EDWARD J. BAKER.
